SPRING CUSHION

Arthur L. Cucuel, Bristol, Conn., assignor, by
mesne assignments, to Cantilever Seat Com-
pany, Incorporated, Wallingford, Conn., a cor-
poration of Connecticut

Application May 28, 1932, Serial No. 614,150

4 Claims. (Cl. 155—179)

This invention relates to improvements in spring cushions and relates more particularly to spring means for cushioned seats such as are employed in automobiles, davenports, and in 5 various other kinds of furniture, and over which a suitable cushion covering may be employed.

An object of my invention is to provide a spring cushion of the above mentioned character in which the spring members are of simple and 10 inexpensive construction.

A further object is to provide a spring member by means of which a substantially uniform degree of resiliency is obtained throughout the entire seating area of the cushion.

15 These and other objects may be more readily understood by reference to the following detailed description taken in conjunction with the accompanying drawings in which:

Fig. 1 is a transverse sectional view of a spring 20 cushion constructed in accordance with my invention;

Fig. 2 is a horizontal sectional view thereof taken on the line 2—2 of Fig. 1;

Fig. 3 is a sectional view corresponding to 25 Fig. 1 but showing the parts in the position which they assume when the weight is substantially evenly distributed upon the cushion;

Fig. 4 is a similar view showing the position 30 of the parts when weight is applied mainly toward the front of the cushion;

Fig. 5 is a similar view showing the position 35 of the parts when weight is applied mainly toward the rear of the cushion; and

Fig. 6 is a horizontal sectional view corre- 40 sponding to Fig. 1 but showing a modified arrangement of the spring members.

In the particular embodiment of my invention herein chosen for illustration in Figs. 1 to 5 45 inclusive, I employ a plurality of spring-members corresponding to each other and each of which is generally designated by the numeral 10, and which are arranged side by side as will be more fully apparent from Fig. 2 of the drawings. Each of the said spring-members presents a substan- 50 tially U-shaped form when viewed either from the top or side, and consists of a pair of comple- 55 mentary upwardly-bowed parallel upper-reaches 11 connected together at their rear ends by an integral cross-reach 12 and each merging at its forward end into a loop or helical coil 13 which has capacity for bodily vertical movement and for that reason may be characterized as a "float- 60 ing" loop, as will more fully hereinafter appear.

Complementing the upper-reaches 11 of each 65 spring-member and of a length substantially

equal thereto is a pair of complementary down- 60 wardly-bowed lower- or base-reaches 14 which merge at their forward ends into the respective floating loops 13 of the spring-member, and at their extreme rear ends are reversely bent in a horizontal plane as at 15 to provide convenient 65 means for anchoring the spring-members to the rear bar 16 of a rectangular frame or supporting-member 17. For the purpose of anchoring the spring-members in place, I employ a 70 clamping-bar 18 which overlies the reversely-bent portions 15 of the respective lower-reaches of the series of spring-members and in turn is secured to the bar 16 of the said frame 17 by means of screws 19 or other suitable means.

It will be noted that the lower-reaches 14 of the spring-members are free throughout their main extent for vertical flexing to enable the loops 13 to virtually "float" in a vertical plane.

Referring to the modification illustrated in 75 Fig. 6, it will be seen by reference to that figure that the spring-members are graduated in size and that the respective cross-reaches 12 thereof are of different lengths. The cross-reach 12 of the largest spring-member extends substantially 80 from one side edge to the other of the frame 17. Each of the remaining spring-members, of which three are shown in Fig. 6, is nested within its next larger complementary spring-member. This latter arrangement is accomplished by progressively 85 differentiating the cross-reach 12 of each of the respective spring-members. The respective base-reaches of each of the spring-members, as shown in Fig. 6, are secured in place in the same manner as are the base-reaches of the spring-members 90 of the preceding figures, and are free throughout their main extent for vertical flexing.

In the foregoing arrangement, the individual spring-members may, if desired, possess different degrees of resiliency to compensate for their dif- 95 ference in size.

An inner covering 20 of flexible material is secured to the side, front and rear edges of the frame 17 and encloses all of the spring-members mounted thereon. Preferably, also, the under 100 face of the said frame 17 is closed against the ingress of dust, etc., by a bottom covering 21.

A pad or cushion 22 is placed upon the upper surface of the inner covering 20 above the spring-members to shield the latter. Over the said pad, 105 as well as over the said covering 20, is applied an outer covering 23 of leather or other suitable flexible material. The respective lower edges of the inner covering 20 and the outer covering 23 may be secured in place to the outer edge of the 110

frame 17 in any approved manner, such, for instance, as by a series of nails or tacks 24.

For a better understanding of my present invention, it may be here stated that the same 5 constitutes an improvement over the spring cushion shown in United States Patent No. 1,369,441, granted February 22, 1921, to one H. Josephson.

The spring cushion shown in the Josephson patent above referred to is one with which I am 10 familiar and which possesses marked defects which it is one of my present objects to overcome. The major defect inherent in the Josephson structure resides in the fact that in such a structure the cushion is relatively rigid, especially at its 15 edge.

In my present invention, I have provided a spring cushion which is freely yielding at both its front and rear edges and at any point intermediate said edges. This latter result is accomplished mainly through the fact that instead of 20 providing stationary and more or less rigid loops or coils, the spring-members of my improved spring cushion are so constructed and proportioned that a "floating" loop, which may have 25 bodily movement in a substantially vertical plane, is provided.

In Fig. 1 of the drawings, the spring-members are shown as in their normal positions and with the side edges of both the inner and outer coverings 30 20 and 23 drawn taut. If, now, weight is applied to the cushion substantially uniformly upon the upper surface thereof, the base-reaches 14 of the respective spring-members will flex downwardly, as will also the upper-reaches 11 thereof. The yielding character of the base-reaches 14, which are of substantially equal length 35 as compared with the upper-reaches 11, permits the respective coils or loops 13 to bodily move vertically.

If, on the other hand, weight is applied mainly 40 to the forward edge of the cushion, the base-reaches 14 of the respective spring-members will flex downwardly and permit the "floating" loops or coils 13 to move bodily downward also, as 45 shown in Fig. 4.

Should for any reason the major portion of the weight be applied to the rear end of the cushion, as shown in Fig. 5, the loops or coils 13 will remain substantially stationary, while the 50 rear end of the respective upper-reaches 11 will be markedly flexed downward, with the further effect of increasing the initially-bowed form of the base-reaches 14.

By so organizing the parts that the loops have 55 a "floating" character and are free to move vertically, I have succeeded in producing a spring cushion, both of the edges of which are resilient, as is also the central area thereof.

It will be understood by those skilled in the art 60 that my invention may assume varied physical forms without departing from my inventive concept, and I, therefore, do not limit myself to the specific embodiments herein chosen for illustration, but only as indicated in the appended claims.

65 I claim:

1. A spring cushion comprising: a supporting-frame having opposite portions respectively extending along opposite, outside, lower edges of the cushion; a plurality of spring-members each having an upper-reach and a complementary lower-reach joined together at one end by a vertically-floating loop normally freely spaced a substantial distance above and overlying one of said opposite portions; the end of the said lower-reach opposite the said loop being anchored to the other of said opposite portions, and the main extent of the lower-reach being normally free for vertical downward flexing to permit the said loop to bodily move downward. 80

2. A spring cushion comprising: a supporting-frame having opposite portions respectively extending along opposite, outside, lower front and rear edges of the cushion; a plurality of spring-members each having an upper-reach and a complementary lower-reach joined together at one end by a vertically-floating loop normally freely spaced a substantial distance above and overlying the portion along the front edge of the cushion; the end of the said lower-reach opposite the said loop being anchored to the portion along the rear edge of the cushion, and the main extent of the lower-reach being normally free for vertical downward flexing to permit the said loop to bodily move downward. 90

3. A spring cushion comprising: a supporting-frame having opposite portions respectively extending along opposite, outside, lower edges of the cushion; a plurality of spring-members each having a pair of upper-reaches connected together at one end by a cross-reach, and a complementary pair of lower-reaches joined to the other end of the upper-reaches by a pair of vertically-floating loops normally freely spaced a substantial distance above and overlying one of said opposite portions; the end of the said lower-reaches opposite the said loops being anchored to the other of said opposite portions, and the main extent of the lower-reaches being normally free for vertical downward flexing to permit the said loops to bodily move downward. 105

4. A spring cushion comprising: a supporting-frame having opposite portions respectively extending along opposite, outside, lower front and rear edges of the cushion; a plurality of spring-members each having a pair of upper-reaches connected together at one end by a cross-reach, and a complementary pair of lower-reaches joined to the other end of the upper-reaches by a pair of vertically-floating loops normally freely spaced a substantial distance above and overlying the portion along the front edge of the cushion; the end of the said lower-reaches opposite the said loops being anchored to the portion along the rear edge of the cushion, and the main extent of the lower-reaches being normally free for vertical downward flexing to permit the said loops to bodily move downward. 120

ARTHUR L. CUCUEL.
